[57] CLAIM

The ornamental design for a needle-less injection instrument, as shown and described.

DESCRIPTION

FIG. 1 is a side elevational view of a needle-less injection instrument with the reservoir laterally positioned and raised, showing my new design;

FIG. 2 is an opposite side elevational view thereof with the reservoir pivoted to the top of the instrument;

FIG. 3 is a front view thereof;

FIG. 4 is a top view thereof; and,

FIG. 5 is a rear view.

FIG. 1

FIG. 2

FIG. 3

FIG. 5

FIG. 4
